TELEPHONE-EXCHANGE SYSTEM.

1,107,136.

Specification of Letters Patent. Patented Aug. 11, 1914.

Application filed August 5, 1905. Serial No. 272,907.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone systems and particularly to exchange systems employing common battery for all purposes. While specially adapted to moderate exchange systems of this type, however, it may 15 be employed with any type of system provided the necessary features are present, as will fully hereinafter appear.

20 My invention has for its object the simplification of the exchange switchboard and the uniform distribution of the load among 25 the operators or among the connective circuits and apparatus.

As hereinafter described, the salient features of apparatus constructed in accordance 30 with the invention are, a constantly rotating arm carrying a plug, a circle of contacts around the arm like jacks, and means operative when the plug comes opposite the contacts of a calling line to project the plug 35 into the jack, stopping the arm and producing the same effect on the line cut-off relay and other pieces of apparatus as when the ordinary plug is inserted in the ordinary jack. Instead of having a circuit connected 40 through flexible conductors to the plug, I prefer to have a pair of bus conductors extend around the circle in proximity to all the contacts of the line jacks, so that when the plug is in any jack the contacts thereof

45 will be closed on the bus-pair. This latter is connected to the cord or equivalent circuit associated with the plug. I am thus enabled to use platinum contacts and to produce absolute certainty in every connection. When 50 a plug has become inserted in a calling jack as stated, and the subscribers have finished the ensuing conversation, they hang up their receivers as usual, severing the line circuits for battery currents, whereupon the supervisory relays act to release the arm carrying the plug, withdrawing the latter and again rotating it in search of a calling line.

55 My invention is illustrated in the accompanying drawing, wherein—

Figure 1 is a diagram showing two sub-

scribers' stations and a central station, with a connective circuit equipped in accordance with the invention. Fig. 2 shows a modified arrangement of the contacts in the selector switch. Fig. 3 is a diagram showing the distribution of the lines among the various selector switches.

In the drawing, A and A' are two subscribers' stations each equipped with the usual transmitter T, receiver R, switch-hook 65 H, ringer Q, etc., suitable for a common battery system. As the apparatus at each station, and the line connections, are the same, I will describe in detail the station A and its connections, only. Here the line wires 1 70 and 2 extend to the central office, where they terminate at the two contacts m and m' of the cut-off relay M, which are normally in closed relation with terminals of the wires 3 and 4 leading respectively to the line relay 75 L and the ground. From relay L wire 11 passes to the bus-wire 12 of the main battery B. The relay controls a local circuit 13 terminating at one contact in each of a series of selectors associated with the operators' cord circuits. This contact is marked 80 o', and when the relay L is excited the contact has its potential raised by connection through the wire 11 to wire 12 and battery. The series of selectors, which are marked 85 O, O', O'', is distributed among the operators in the exchange in a manner to be presently pointed out, and the moving parts of those selectors which carry the same lines are arranged to be a synchronous, or out of step, 90 so that a calling line will be caught up by the first selector of its set which reaches its terminal after the call is initiated, and by no other.

95 Each line has multiple terminals for calling, in the banks of the selectors, and multiple jacks for being called, on the switchboard panels. The multiple calling terminals of line 1—2 are marked o', as already stated, and they are connected to wire 13. 100 They are accompanied by talking terminals, separate from the signaling or calling circuit, lettered o'' and o'', and shown only in switch O, although they also appear in the switches O' O''. In the diagram they are 105 omitted from the latter switches for the sake of clearness and simplicity. The multiple calling terminals of the line 41—42 also appear in the various selectors, being indicated by the letters o''' 110, and their circuit wire by

the number 100, connected when the relay L' is excited to the battery wire 12 through the branch 110. The talking contacts of line 41-42 are connected through the branches 35-36 to wires 37-38, these corresponding to the wires 5-6-7-8 of line 1-2. The normal line connections of line 41-42 are by way of wires 39 and 40, corresponding to 3 and 4 of line 1-2. The interconnection of these lines is through a cord circuit as usual, and it is to be understood that I preserve the conditions now relied upon for busy test and for supervision, at least of the called line. No supervision of the calling line in any particular connection is necessary, for the reason that the calling subscriber of a connected pair has it in his power to disconnect himself as soon as he is through talking. This will appear later from the description of the cord circuit apparatus, which I will now give. Broadly stated this comprises four relays, two supervisory lamps, and a selector, the latter taking the place of the answering plug, for to this extent it is a single cord system. There is only one operator's plug to a cord. There is another plug, but it is in the selector machine, and is automatically operated. The selector answers the call, putting the subscriber on the cord circuit. The operator then gets the first signal through the lighting of the calling supervisory lamp, and comes on the line calling, through the usual listening key, or through an automatic listening device, to obtain the number wanted. This obtained, she tests the line wanted and completes the connection by sticking a plug as in ordinary systems heretofore employed.

The selector I here present comprises a constantly driven shaft N, with collars carrying individual arms, carrying contacts o which are constantly sweeping over circularly arranged series of coöperating line contacts o'. The shaft in the present case is shown as driven through a belt n' and a pulley n, but it will be understood that the driving means may be of any suitable description. The several selectors are all driven by preference on or from the same shaft, so as to secure not only economy of power and transmission but perfect uniformity in speeds and synchronous movement of those selector arms which may sweep over multiples of the same lines. An individual selector mechanism such as I have shown at O in Fig. 1 comprises a sleeve or collar o¹³ loosely mounted on the shaft between fixed collars o¹⁴-o¹⁵, and fitted with a projecting tubular arm carrying the windings o⁹ upon it and the combination core or plunger o¹⁰-o¹² within it, the arm thus constituting in effect a solenoid with a plunger core. On the outer head of the magnet winding a cap or casing o¹⁸ is provided to house a spring o¹⁹ by which the

plunger is normally kept retracted toward the shaft, as shown in the figure. The function of this plunger is two-fold. In the normal or idle condition of the parts it serves as a locking detent or clutch to hold the sleeve o¹³ fast on the shaft; its end projecting at such times into an opening or socket in the shaft as indicated at o¹². When the arm is opposite a calling line terminal the plunger is thrown forward and its outer end enters the jack ring o⁷, the inner end at the same time leaving its socket in the shaft, thus stopping the sleeve and arm and spreading the jack springs to complete the cord and line connection. The inner end of the plunger, o¹¹, is of soft iron, with a hard tip if necessary. Its outer end, o¹⁰, is of insulating material such as hard wood.

The winding o⁹ is double, consisting of an inner and outer layer, like the primary and secondary of an induction coil. The outer winding is connected on one side to the contact spring o through the wire 43, and on the other side by wire 50 to ground through the normally closed back contact of the relay R^a and wires 48 and 44. The inner winding of the solenoid is connected on one side direct to ground and on the other by wire 14 to wire 15 and the front contact of the supervisory relay R. Of course these two windings of the solenoid may be put on the tube in any desired fashion. They may be end-on instead of inner and outer, or in alternating layers, but the simplest method is that I have indicated. The only requirement is that the winding connected to contact o shall be able to pull in the core o¹¹ when energized, and that the winding connected to wire 14 shall be able to hold the core in when so attracted.

The cord circuit terminates at the answering end in the bus contacts o⁵-o⁶, each a ring with its inner edge cut into a comb, having a tooth for every line on the selector. These two combs, top and bottom, forming the two side terminals of the cord, may be spread to close on any pair of individual line contacts o²-o³ by the plug or plunger o¹⁰, the line contacts being arranged in a radial series, as indicated in the switches O' and O². When the plunger arm is opposite a particular pair of line contacts, if the solenoid then gets current the plug will be thrown forward and between the two teeth of the combs o⁵-o⁶ at that point, spreading them against the line contacts. All these contacts are supposed to be fitted with platinum points at the ends, and each tooth of each comb with corresponding platinum contacts. Mechanically, the structure comprising the combs and line contacts is built up by superposing the contacts upon each other with interposed insulating rings in a manner well understood by those skilled in the art. This structure is not shown in detail in the drawings, except as to the arrangement of one

pair of line springs and their coöperating parts in the selector O. The assembled structure o^{12} is supposed to extend around the shaft and sleeve o^{13} in a continuous ring, so that as the arm is turned the contact o will continuously sweep over the series of line signal contacts o' .

Contacts o^5 and o^6 are connected by wires 9 and 10 to the condensers C—C', and these on the other side are connected by wires 26 and 27 to the tip and sleeve respectively of the plug P. The two bridges which appear in all standard common battery cord circuits are here present, at 19—20 and 21—22. In the first bridge are the relays R and R^2 , and in the second are the relays R' and R^3 . Interposed in both bridges between the relays is the main battery B, and as the condensers fall between the bridges the battery feeds both ways, as usual, with control of the relays R and R' given to the respective subscribers who may be connected through the cord. Relay R has its lamp S connected from its front contact to ground, and its armature connected by wire 16 to the front contact of the relay R^2 . The inner winding of the solenoid o^9 is also connected to the same contact of relay R. Relay R^3 has its lamp connected from its back contact to ground and its armature to the front contact of relay R^2 . This relay R^3 has a second armature which, through its normally closed back contact controls the continuity of the ground wire 44—48 to the lamp S, the relay R and the solenoid o^9 .

It will be understood that I have spoken of the wires 19—20 and 21—22 as bridges as if they were continuous, which in effect and in practice they are. As shown grounded circuits are used for convenience of illustration. It is much easier to trace circuits and to perceive differences of potential at different points in a diagram of this kind.

31—32 represents a listening key adapted to bridge the operator's telephone circuit 33—34 across the answering end of the cord, and 28—29 represents a ringing key of the usual type adapted when actuated to connect the generator circuit 30—30' to the calling plug P, at the same time disconnecting the plug from the cord and condensers so as not to ring back. These listening and ringing appliances may be combined into one, or they may be replaced by automatic appliances which will at the proper times cut in and out the operators set and the ringing generator.

The operation of my improved system will now be understood. The shaft N is supposed to be constantly rotating, carrying with it a number of selectors. I contemplate having one selector for each cord circuit, but with the better distribution of business this will bring about the number of cords can probably be decreased at least 15%, so that

instead of twelve pairs of cords and plugs there will only need to be ten, and perhaps less. For each operator, then, we may assume there are ten of the selectors, which in an exchange of 5,000, would mean 500 selectors. Each selector preferably has 100 line contacts or pairs o^2 — o^3 , over which its arm sweeps. If the same lines were multiplied to the same contacts in all the ten selectors on one position of the board, that is if all the lines were located just as they now are, with their answering terminals before the same operator for a given number, and that operator only, the gain would not be so great from my invention. Since each selector has 100 lines on its bank, however, 50 selectors will afford one connection each for the entire 5,000 lines, and 500 selectors will enable the lines to have ten multiple terminals each. Instead of multiplying them on their own 85 positions, I distribute these multiples of each line among ten different operators. In other words, as in the figure, the wire 13 is carried to the contact o' of selector O, which we will assume is associated with position 90 number 1, then to contact o' of selector O' which we will assume is associated with position number 2, and so on. This line will then have a multiple in each of ten selectors associated with each of ten positions or each 95 of ten operators. Instead of carrying the multiples down to selectors 1, 2, etc., in order, the wires may be multiplied from position 1 to position 3, thence to position 5, or to 2, 4, 6, or in fact in any order that 100 when all the lines are finally multiplied will give a fairly uniform distribution. The notches or sockets o^{12} of the various selector arms in the common shaft are set helically to each other, or if they are all set straight 105 along the shaft the line contacts are connected helically, so that only one arm will make contact with the same line contact at the same instant. As a line is multiplied ten times, or to ten selector switches, it follows 110 that the ten notches of these ten switches must be set around the shaft step by step, so that the arms will project like the steps of a winding stairway, in a helix. Thus when a line calls only one selector will touch 115 it at once. Otherwise several or all the ten might connect with the same line and interfere. If it be desired to have the selectors all one sided, that is with their notches all in a line, the line wire 13 must be connected 120 to contact number 1 in the first selector, to contact number 2 in the next selector, to contact number 3 in the next, and so on. This achieves the same end, but it should be observed that it is preferable to carry around 125 the notches, because then the shaft is balanced in its rotation, since the arms will for an exchange of any size form a recurring spiral of several successive turns per section. If the arms are all on one line, the shaft 130

will need strong and heavy bearings, particularly if it is to rotate with any speed, which is desirable in order to cut down the time of reaching a calling line. Another way of reaching a balance for the shaft is to make the arms double, that is extending out on each side of the shaft, with two solenoids, two contacts o' , etc., for each sleeve o^{13} . The contact banks o^{16} , instead of being circular may then be semi-circular, lying all on one side of the shaft as is shown in Fig. 2. The sweep over the contacts will be continuous as before, because one arm of a pair will be leaving the bank on one side 15 on its rotation when the other arm is just coming on. The radius of the circle is increased by this arrangement, but an advantage is that the shaft and its connections are exposed and any contact bank can be 20 moved bodily.

In addition to the helical arrangement of contacts or arms, I may practise various methods of distributing the line contacts to gain perfect equality of load on all the operators. It will be observed that the 100 lines that appear on the same selector in number 1 position according to the arrangement I have outlined heretofore might appear together at each position where they 25 had multiples. An operator would thus be limited to 1,000 lines for her selective portion of the entire number, and the ten operators who had a given thousand lines thus apportioned to them as their complement 30 would assist each other but no operators beside. Their load would be averaged among themselves, and if their 1000 lines all got busy at once the rest of the exchange might be idle and it would avail them nothing. In order to avoid this, a further distribution scheme which is shown in Fig. 3 is this: Assume lines to be connected on number one selector of number one position (1P of Fig. 3) in serial order, that is 35 1¹, 2¹, 3¹, and so on. Line number 1 would go to contact number 2 in selector number 2 on position number 2, to contact number 3, selector number 3, position number 3, and so on. Line number 2¹ would go to contact 40 number 2 in selector number 1 of position number 1, thence to contact number 3 in selector number 3 of position number 2. Line number 3¹ would go to contact number 3 in selector number 1 of position number 1, 45 thence to contact number 4 in selector number 4 of position number 2, and so on. By this means, or by means of any equivalent arrangement, the even multiplying of the first 100 lines is broken and the lines distributed 50 as to their potential calls among practically all the operators for all the lines, or at least each group is so distributed. That is to say, instead of the same 100 lines going to ten operators, each line would go to ten 55 operators but only two lines would go to

the same operator more than once. In a ten thousand line exchange with this arrangement and the same decimal provision, since there would be 100 operators, each operator would have 1000 lines on her selectors, but they would be compounded of groups of ten, one group from each other operator, or one from each selector in the exchange. Thus no two lines need to be associated on the same position more than 60 once.

The multiple connection of the contacts of the selectors being symmetrical and regular, the progression I have mentioned can be made in wiring by simply twisting the 65 cable enough to bring number one wire to number two contact, etc. This wiring is done in the factory, and will offer no difficulties at all.

In the diagram, suppose subscriber A is 70 calling and desires connection with subscriber A'. He simply removes his receiver R from its hook, and waits the operator's answer. The line circuit being thus closed, current through the relay L energizes it, 75 and the armature closing circuit 11-18, the potential of the test contacts o' of the line in all the selectors to which it is connected is raised. The first selector whose arm contact o comes on the live terminal o' picks 80 up the line. As soon as contact o touches contact o' , current passes from battery by the following circuit: B, 12, 11, l, 13, o' , o , 85 43, o^9 , 50, 48, 44, ground, B. The solenoid being thus energized, core o^{11} is at once 90 pulled into the tube, withdrawing its end from the notch o^{12} and freeing the arm from the shaft which continues to rotate. At the same time the plug end o^{10} of the core is 95 pushed forcibly into the jack opening in the 100 sleeve ring o^7 and between the spring teeth o^5 - o^6 , spreading them apart against the line contacts o^2 - o^3 of the calling line. The instant this occurs, current finds a new path from the battery as follows: B, 12, 18, 17, 105 110 R^2 , 20, 10, o^8 , o^3 , 8, 6, M, ground, B. This energizes the relay R^2 and the cut-off relay M, which immediately pulls up its armatures and disconnects the line relay L, connecting the line wires 1 and 2 at the same 115 time to the wires 5 and 6 whence they are connected through 7 and 8 to o^2 - o^3 , to o^5 - o^6 , to 9-10. Current from battery B now flows to line through the conductors 9-10 and the relays R^2 and R. The latter 120 immediately pulls up, closing the battery circuit as follows: B, 18, 17, 16, 15, 14, inner winding of o^9 , 45, and ground to B. This holds up the core of the solenoid before it has time to withdraw, being rather sluggish in its action. The magnet L is of course cut off as soon as plug o^{10} is in, and the potential of the contacts o' is dropped to normal, so that no other arms will stop thereon. A branch of the last circuit is from 125 130

wire 14 through the lamp S to wire 48, 44 and ground to battery. The lamp lights, thus advising the operator of the call and that the line calling is on the cord 9—10. 5 Relay R is self-locking. That is, it has an armature grounded through the wire 46 which when pulled up will close upon a contact 47 connected to the winding and will thereafter hold itself up as long as the plug 10 circuit is in use and the plug o^{10} in the jack. The operator, perceiving the signal, comes in on the cord through the key 31—32 and gets the number wanted. She tests the line with the tip of plug P in the usual way, 15 and completes the connection, by inserting the plug in one of the multiple jacks J—J' which happens to be within her reach. As soon as this plug is in the jack the relay R³ gets current by the following path: B, 18, 20 23, R³, 22, 29, 27, p, j, 38, cut-off relay and ground back to battery. The cut-off relay of the called line is thus energized and pulls up, putting the line wires 41—42 onto the jack wires 37—38, and the operator then 25 uses the calling key 28—29 to ring the subscriber A'. The energization of relay R³ produces another and quite as important an effect as that of supplying current through wire 24 for the supervisory lamp S', which 30 so long as the called subscriber does not answer remains illuminated. I refer to the removal of the ground from wire 48. This is necessary for two reasons. The lamp S having performed its only function when it 35 called the operator's attention to the call, must now be removed from operative connection, and the ground must be taken off the solenoid o^9 to prevent its coming back on the same line for a recall and before the 40 operator has had time to remove the plug P of the original connection. This will appear in a moment more clearly. The subscriber A' having answered and the subscribers having finished their conversation, 45 suppose A' hangs up first, and A keeps his receiver down for a recall. The operator pulls the plug P, relay R³ loses current and lets go, the ground comes back on lamp S and it lights, whereupon the operator comes 50 in on the cord again by key 31—32 for instruction. As the operator does not receive a signal from A when he hangs up, he may keep his receiver down and wait for recalls in succession, taking his chance of the 55 promptness of the operator. Suppose, however, a better way, that A and A' both hang up. Relay R' lights the lamp S', and relay R lets go its armatures, cutting off its own ground, and also taking battery off the 60 winding of solenoid o^9 which it controls. The solenoid thereupon lets go its core-plunger, the spring o^{10} pulls the plug o^{10} out of the jack o^7 , and the same operation having coupled the sleeve o^{12} onto the shaft

again it starts to rotate as before. It will 65 be observed that the heel of the plunger will ride on the surface of the shaft until the notch comes opposite. This always positions the sleeve and arm correctly. It should be here remarked that the notch o^{12} may 70 be replaced by a projection or stud, which will push the arm around by catching the end of the plunger. In such case the sleeve o^{12} should have a groove to permit the free 75 passage of the stud under the end of the tube carrying the solenoid. The selector O will not again pick up a calling line after such disconnection as just noted, until the plug P has been again disengaged from the jack J. The reason for this is that the relay 80 R³ letting go its armature only when the plug is pulled, the ground is off the solenoid until that happens. Even if by accident, however, the same or another line should come back on the selector, the relay R has 85 also lost its ground and would not hold up the solenoid core. This latter precaution is not a necessity, however, as the likelihood of the selector picking up a line without a ground on the solenoid is very little. 90

Suppose A hangs up first and A' is careless and does not follow suit. The relay R lets go, and the selector is released as before, but it remains idly rotating until A' has hung up and the operator has pulled the 95 plug P. A, in the meantime, can go ahead and make other calls, getting on other selectors by so doing. When A' finally hangs up the operator can disconnect in the usual manner. If she notes a connection persisting for too long a time she can listen in or break it. It is thus impossible for subscriber A' or the called subscriber of a pair to hang up the calling subscriber. By my system, however, it is equally impossible for 100 the called subscriber to be hung up. Suppose A fails to clear out. The moment A' restores his receiver to the hook his supervisory lamp S' lights and the operator knows she is to pull the plug. The instant 105 she pulls the plug the lamp S will light if A has his receiver down, and she can deal with him in the usual way.

Having thus described my invention, what I claim and desire to secure by Letters Patent of the United States is:

1. In a telephone exchange system, a plurality of subscribers' lines, a cord circuit having its answering end terminating in an automatic selector switch and its calling end 120 terminating in a plug, answering terminals for two or more of the subscribers' lines in said selector switch but normally disconnected from the cord circuit terminals thereof, and a spring jack or jacks for each 125 subscriber's line, together with means associated with the said terminals of the selector switch adapted to be brought under the

- control of a calling line to thereupon initially effect connection of said line terminals to the cord circuit terminals. 65
2. In a telephone system, a plurality of subscribers' lines, a cord circuit having its answering end terminating in an automatic selector switch and its calling end terminating in a plug, answering terminals for two or more of the subscribers' lines in said selector switch, and a springjack or jacks for each subscriber's line, together with means associated with the selector switch adapted to be brought under control of a calling line in the act of calling to thereupon initially effect connection of said line through the said switch with the cord circuit, and a signal becoming operative upon the completion of said connection, and remaining operative throughout the continuance of said connection, substantially as described. 70
3. In a telephone exchange system, a plurality of subscribers' lines and a cord circuit for interconnecting them terminating at its calling end in a plug and at its answering end in an automatic selector switch comprising the following instrumentalities: a constantly rotating shaft carrying an arm, a series of contacts each connected to a subscriber's line, an associated common contact for the cord adapted to be brought into connection with any line contact by said arm, a calling contact in said switch for each line and associated with its line contact, and means associated with the arm and shaft co-operating with the calling contacts to stop the arm and connect the terminals of a calling line to the cord terminal or terminals, substantially as described. 75
4. In a selector switch for cord circuits a constantly rotating shaft, a sleeve detachably connected to rotate therewith, a tubular arm on said sleeve and carrying a solenoid winding, a movable core within the tube having its end controlling the engagement of the sleeve and shaft, and contacts in the switch co-operating with the tubular arm, substantially as described. 80
5. In a selector switch a constantly rotating shaft, a tubular arm carrying a solenoid upon it and a reciprocating core therefor within it, a clutch between the arm and shaft at one end of the core and a plug at the other end, and a series of contacts co-operating with said plug, substantially as described. 85
6. In a selector switch for telephone systems a constantly rotating shaft, a sleeve thereon, a tubular arm on said sleeve having a solenoid winding upon it and a reciprocating core within it, a clutch controlling the engagement of the sleeve and shaft at one end of the core and a plug at the other end, a circular series of line contacts and a calling contact associated with each, a sweeping switch contact connected with the solenoid and said contact to bring the solenoid successively under control of the several lines through the several calling contacts, substantially as described. 90
7. In a semi-automatic telephone exchange circuit, a line circuit, a relay therefor with a source of current supply, a constantly driven selector switch mechanism having a traveling plunger and being connected with a plug terminal, and means whereby said line relay may control the switch mechanism to stop the plunger and thus produce connection with the line when calling, substantially as described. 95
8. In a telephone exchange system, a plurality of line circuits each having a line relay, one or more connection jacks and a plurality of multiple answering jacks, together with plugs automatically controlled by the line relays for making connection with said answering jacks in response to calls, substantially as described. 100
9. In a telephone exchange system, a plurality of line circuits terminating in multiple answering jacks, a constantly driven connective device provided with a plunger and arranged to force the latter into a jack of a calling line on the closing of the subscriber's line circuit. 105
10. In a telephone exchange system, a plurality of line circuits provided with multipled answering jacks and having one or more connection terminals, an operator's cord circuit and a constantly driven connective device associated therewith and provided with a movable plunger adapted to be forced into the answering jack of a calling line on the closing of the subscriber's line circuit. 110
11. In a telephone exchange system, a plurality of lines to be interconnected, a plurality of link circuits for effecting said interconnection and including a line seeking switch at one end having test terminals for the lines and a test relay associated therewith and adapted to stop the switch at any given line, a battery supply relay at the calling end of said link, an energizing circuit therefor completed upon connection made to the called line, said test relay having test circuits completed initially through said test terminals and through a contact under control of the said battery supply relay, whereby the circuit of said test relay is opened when connection with the called line is made. 115
12. In a telephone exchange system, a plurality of lines to be interconnected, a connecting link therefor having a line seeking switch at one end thereof containing a plurality of line terminals together with co-operating link terminals adapted to be connected directly therewith but normally con-

tinuously disconnected therefrom during the travel of the switch, and means responsive to a call over any line to effect connection of the said link terminals with the answering terminals of the calling line when the calling line is reached.

13. A telephone exchange system comprising a plurality of subscribers' lines to be interconnected, a connecting link therefor having a line seeking switch at one end including a plurality of line terminals together with coöperating link terminals normally disconnected therefrom in travel but adapted to be connected directly therewith, line 15 test terminals also in said switch, a wiper therefor, and means controlled through said test terminals and wiper and responsive to a call over any line to effect the aforesaid connection of the link terminals with the 20 answering terminals of the calling line, when said calling line is reached.

14. In a telephone exchange system, a plurality of subscribers' lines to be interconnected, a link circuit for effecting said interconnection having a line seeking switch at one end thereof, means for actuating said switch, means associated with the link and controlled from any calling line to stop the switch in connection with any calling line, 25 and a tip relay for the link, together with holding means for said switch in its actuated positions controlled by the said tip relay of the link independently of connection with called lines.

15. In a telephone exchange system, a plurality of subscribers' lines to be interconnected, a link circuit for effecting said interconnection having a line seeking switch at one end thereof, means for actuating said switch, means associated with the link and controlled from any calling line to stop the switch in connection with any calling line, 40 and a tip relay for the link, together with means governing the release of the line seeker from the calling line controlled by the said tip relay of the link independently of connection with called lines.

16. In a telephone exchange system, a plurality of lines to be interconnected, a link 50 containing an automatic line seeking switch for effecting said interconnection, means controlled from calling lines to cause said switch to seek and make connection of the link with any calling line, a tip battery supply relay on the answering end of said link energized through the line seeking switch, and retaining means for said switch in its actuated positions controlled exclusively by said battery supply relay.

17. In a telephone exchange system, a plurality of lines to be interconnected, a connecting link containing an automatic switch, actuating means for the switch, a tip battery supply relay energized from the subscribers' lines through said automatic switch

when connection is made, and retaining means for the switch in any of its actuated positions controlled exclusively by said battery supply relay.

18. In a telephone exchange system, a plurality of lines to be interconnected, a link circuit for interconnecting the same containing an automatic line seeking switch, sleeve battery supply relays at the answering and calling ends of said link respectively, actuating means for said switch, means to stop said switch in connection with any given line controlled over a circuit including normally closed contacts of the sleeve relay of the calling end of said link, a tip relay at 75 the answering end of said link, and means for retaining said switch in actuated positions controlled through normally open contacts of said tip relay.

19. In a telephone exchange system, a plurality of lines to be interconnected, a link circuit for interconnecting the same containing an automatic line seeking switch, sleeve battery supply relays at the answering and calling ends of the said link respectively, 80 actuating means for said switch, means to stop said switch in connection with any given line controlled over the circuit including normally closed contacts on the sleeve relay of the calling end of said link, a tip relay at 85 the answering end of said link, and means to retain said switch in any actuated position controlled jointly by normally open contacts on said sleeve and tip relays of the answering end of said link.

20. In a telephone exchange system, a plurality of lines to be interconnected, a link containing an automatic switch for interconnecting them, actuating means for said switch, means under control from the subscribers' lines to bring said switch to rest in connection with any calling line, and a pilot lamp remaining lighted during the period of rest of said switch in connection with any line.

21. In a telephone exchange system, a plurality of lines to be interconnected, a link containing an automatic switch for effecting said interconnection, actuating means for said switch, a battery supply relay energized through said switch from the subscriber's line, together with retaining means for said switch in its actuated positions and a pilot lamp remaining lighted during the period of rest of said switch in connection with any line, controlled in common by said battery supply relay.

22. In a telephone exchange system, a plurality of subscribers' lines, a link containing an automatic switch for effecting interconnection between said lines, said switch comprising a normally continuously rotating plug and a plurality of stationary contacts adapted to be engaged by said plug through longitudinal movement thereof, an actuating

ing winding for said plug controlled from any calling line, and a holding winding for said plug also controlled from the calling line.

- 5 23. In a telephone exchange system, a plurality of lines to be interconnected, a link containing an automatic switch for interconnecting them, said switch comprising fixed terminals and a movable contact-making element, the said movable element being adapted to travel over the said fixed terminals in dissociated relation thereto to a point opposite the terminals of any calling line,

means controlled from the calling line to effect association of said movable and fixed elements to make connection of any line with said link, and means also controlled from the calling line to retain said elements in the aforesaid connective association during the continuance of any call.

20 In testimony whereof I affix my signature in presence of two witnesses.

EDWARD E. CLEMENT.
